COMBINED TYPEWRITING AND COMPUTING
MACHINE

Henry L. Pitman, Westfield, N. J., assignor, by
mesne assignments, to Underwood Elliott Fisher
Company, New York, N. Y., a corporation of
Delaware

Application August 2, 1930, Serial No. 472,610

60 Claims. (Cl. 235—60)

This invention relates to combined typewriting and computing machines, such as the well-known Underwood bookkeeping machine, in which the numeral-type-keys set up elements of an indexing mechanism, which is used to run the corresponding digits into one or more totalizers at the cycling of a general operator, after the complete number is typed upon the work-sheet.

When passing through an adding zone, the paper-carriage at every step displaces an index-pin-carrying bar, bringing its pins into the paths of pin-setting devices that are operable by the type-keys. The general operator thereafter drives the bars according to the settings of the pins, and these bars are caused to rotate the register-dials. The pin-bars have trains that extend up in rear of the paper-carriage, and are operated seriatim by means of a tappet or dog that is attached to the paper-carriage. A machine of this general description is seen in the patent to Hart, No. 1,190,171, of July 4, 1916. The present invention relates partly to improved means for displacing the pin-bars by the operation of the paper-carriage.

The principal objects of the invention are to provide a simple, inexpensive and reliable machine of the class referred to, and one of the aims is to improve the type of machine in which a single set of denomination-selecting trains is operated by the carriage, and ramifies to several registers, or to several register-operating index-pin-bars. In this type of machine, there is employed a set of horizontal rock-shafts that extend across the machine in its rear portion, and from these shafts depend branches or arms, the latter arranged in sets, there being one set of arms for each set of pin-bars. The rock-shafts and all their arms, however, are driven by means of a single set of operating arms provided upon the shafts. These arms receive impulses from a single set of master-rods that extend down from a point near the paper-carriage at the rear of the typewriting machine.

Hence, the carriage-tappet, in acting upon any denominational train, operates through the rock-shaft to vibrate simultaneously as many arms or distributors as there are registers in the machine, and to advance or set the pin-bars of the selected denomination, so that while the paper-carriage remains stationary, the operation of any numeral-key causes one index-pin-bar to be set for each of the registers. Similar operation may take place at every letter-feeding movement of the carriage through an adding zone. At the cycling of the general operator, the typed and

indexed number is carried into all of the registers, although the carriage has traveled through but one zone, and has actuated only the master set of connections.

Each of the transverse rock-shafts carries a rearwardly-extending operating arm, and at their rear ends these arms form a transverse row, and rods extend upwardly therefrom terminating at their upper ends in novel vertically slidable jacks having beveled tops capable of being pressed down seriatim by means of a beveled tappet which is mounted upon the carriage.

It is desired to adapt the mechanism for use with Underwood bookkeeping machines of standard construction, and for this purpose the extent of movement of the horizontal master-arms is made to equal the extent of movement of the pendent distributive pin-bar-setting arms. It is desired that the latter should terminate in a transverse level row at their lower ends, and that the master-arms should terminate in a row transversely of the machine, and also that the rods that extend down from the jacks should also occupy a single transverse vertical plane; and to accomplish these results, said set of rock-shafts is arranged in an inclined transverse plane. The rock-shaft arms in all of the sets are of graduated lengths, all being operated by equal movements imparted by the typewriter-carriage, and imparting equal movements to the index-pin-bars.

The first of the denominational trains that is operated by the carriage is the train of highest denomination, and the last is of lowest denomination. Accordingly, the master-arms upon the denominational rock-shafts are arranged in reverse order, their denominations proceeding from highest to lowest towards the left. The distributing arms upon the same rock-shafts, however, are arranged in the natural denominational order, that is, proceeding towards the right from highest to lowest denomination. In other words, the master-arms have a transposed arrangement with respect to the distributing arms.

It is desired, during the power return of the paper-carriage, to avoid camming down the denominational jack-trains, and accordingly each train is made in portions, and by means of an automatic device one portion is separated from the other in each train, and the jacks drop out of the way of the carriage-tappet.

The carriage-tappet is settable along the carriage, fitting between the teeth of a carriage-rack. It is used also for carriage-tabulating purposes.

A further feature of the invention relates to improved means for enabling one or more adjustable teeth or blades upon the paper-carriage to select a register or registers for operation in any computing zone. Register-selecting trains, one for each register, rise to the carriage, preferably at the rear of the aforesaid denominational indexing trains, to position to be operable by said carriage teeth or blades.

It has been explained that each denominational rock-shaft carries a number of distributive pendent indexing arms, one for each register. These distributive arms are connected by couplers which engage shoulders provided upon the pin-bars. The couplers for every register are normally disabled. Said carriage-teeth, however, select the cams, one cam being provided for each register-selecting train. The cams are grouped facewise at the middle of the machine.

The function of each cam is to operate its train and lift the set of couplers that belong to the register corresponding to the cam, so that the indexing for that register will proceed while the carriage is passing through any given computing zone. Each cam is in the form of a plate having a dwell portion, whereby the carriage-teeth are enabled to maintain the selecting trains in their effective positions throughout the zone. Hence, the number being typed may be computed in the desired register, while any one or more of the remaining registers remain idle.

Each register-selecting train may include an upstanding two-part rod which is thrust down by the cam-plate, and a lever extending forwardly from the rod and pivoted between its ends; its rear arm being thrust down by the rod, and its forward arm serving to lift the couplers to effective positions.

After passing out of the computing zone, the carriage-tooth rides off from the cam-plate, and the couplers for that register drop again to idle positions.

In order to provide for the selection of any two or more registers for operation in any one zone, the carriage may be provided with as many selecting teeth as there are registers, and these teeth may operate simultaneously to couple the selected sets of index-pin-bars with the rock-arms, for displacing the pin-bars, so that the number being typed may eventually be run into all of the selected registers.

Any desired number of these adjustable register-selecting teeth may be employed, and they control the selection of registers for only one computing zone at a time. There may be arranged as many groups of adjustable register-selecting teeth as there are computing zones on the work-sheet, and any desired number in each group for selecting any desired register or registers for the various zones.

The register-selecting cam-plates operate vertical rods arranged in a rearwardly-extending diagonal row. The cam-plates may be duplicates, and interchangeable, and any one can thrust down its desired register-selecting rod in the diagonal row. The length of a register-selecting cam-plate is as great as the width of a computing zone on the work-sheet.

It has already been explained that an adjustable denomination-selecting dog is provided upon the carriage having means to fit in notches in a column-stop rod, and is combined with a carriage-tabulating column-stop. The same adjustable device is also combined with a register-selecting tooth or teeth, and is adjustable as a

unit along the carriage, so that by one setting there is made the proper provision in respect to any given zone for tabulating, denomination-indexing and register-selecting. This adjustable combination device includes a block that has a series of notches, said series extending rearwardly, and in the notches there may be introduced the teeth, which may be fastened by a pin passing through a hole in the block. These teeth may be set into any desired notches in the block, and for the purpose of bringing into operation any desired registers in the zone for which the combination device is set. The teeth may be reset in different notches from time to time. The combination device may be used in any zone, and a variety of them, with different teeth-settings, may be kept on hand.

When tabulating, the carriage is brought to rest a little in advance of its true typing position. After the tabulating key is released, the carriage has a short drop to typing position, and during this short drop the first denomination jack is depressed by the carriage-tappet.

The set of carriage-tabulating decimal-stops is so located with relation to the set of denomination jacks that the carriage, upon being tabulated, reaches the proper point to begin the indexing for the adding operation.

During the return of the carriage by a power-drive, the denomination jacks may all drop out of the path of the tappets on the carriage. There is provided a carriage-return key, and the usual power train is operated thereby to control the return of the carriage. This train is connected to a linkage which swings the upper set of the vertical denominational links or rods away from the lower set, where they remain while the carriage is returning. This disconnection of the denomination train takes place when the carriage is being tabulated. When the tabulating key is released by the operator, the denomination mechanism is restored to working position.

The dropping of the denomination jacks also occurs automatically at the operation of the case-shift key of the typewriter.

It will be remembered that both the train of denomination-indexing devices and the train of register-selecting devices extend from the upper part of the typewriter down to the adding mechanism in the adding base under the typewriter. It is desired to take the typewriter off from the adding base, and according to the present improvements an advantage is gained by having the vertical rods in each group consist of upper and lower portions separable from each other. Each upper portion extends down back of the typewriting machine, and each lower portion extends up from the base. The typewriter is clamped upon the base, and hence when it is desired to remove the typewriter to give access to the adding mechanism it is only necessary to release the clamps, and then lift the typewriting machine right off from the base, without the necessity of giving attention to the detachment of denomination and register selecting trains.

Another feature of the invention is the automatic dropping of the register-selecting cam-plates during the cycling of the general operator of the adding mechanism. For this purpose, there is connected to the general operator shaft a disk, which is provided with a notch on its periphery. This notch is normally occupied by a roll provided upon an arm, and the arm disconnects the lower members of the register-selecting rods, and keeps them disconnected dur-

ing the cycling of the general operator, permitting the upper members to drop, together with the cam-plates.

This disconnecting mechanism is mounted in the adding base, where it is operable by the general operator, while the denomination-jack-disconnecting device is mounted in the typewriting machine, where it is always under the control of typewriting mechanism, and is lifted off from the base therewith.

All of the register-selecting trains form a central group at their carriage ends, and extend down side by side into the adding base and there diverge. The first of said trains is connected to control the activity of the register at one extreme side of the machine. The next train controls the next register, and so on, there being one train for each register.

The connection from the outermost register to the central group includes a rock-shaft carrying an arm to lift a bail, in which are carried the free ends of the couplers that set forward the index-pin-bars. The raising of any set of couplers connects its set of pin-bars to the indexing jacks at the paper-carriage.

The coupler-lifting bails for the second and other registers are lifted by means of arms which extend to the register-selecting rods. The registers at the sides and middle of the system are thus properly connected to the central controlling group rods.

The adjustable combination device, which carries the tabulating stop, the denomination-selecting dog and the set of register-selecting dogs, is supported upon two racks that are placed one behind the other on the paper-carriage, the device fitting in the notches in both racks. The rear end of the device has a ridge upon its top, to mesh with the teeth in the under side of the rear rack.

At the middle portion of the machine, where the denomination jacks and the register-selecting cams are located, there is provided a fixed horizontal guide or key, which may be in the form of a flange bent forwardly from a vertical fixed plate; and each of the combination devices has a notch in its rear end, which fits upon said key, thereby insuring proper co-operation of the device with the register-selecting cams, as well as with the denomination jacks. In front of the devices, there is provided upon the carriage a scale, and the upper prong of each device points to said scale to facilitate adjusting the device along the carriage.

Provision is made for key-locking jacks to occupy punctuation spaces in the row of jacks.

When the general operator cycles, the numeral-keys of the typewriter are automatically locked against operation. The keys are also locked while the carriage is returning.

Other features and advantages will hereinafter appear.

In the accompanying drawings,

Figure 1 is a rear perspective view, showing the method whereby the general operator effects disconnection of the denomination-selecting trains. This view also shows trains for locking the digit-keys at the punctuation spaces.

Figure 2 shows an index-pin-bar provided with a hardened shoulder.

Figure 3 is a sectional side elevation taken about centrally of an Underwood bookkeeping machine reconstructed according to the present improvements.

Figure 4 is a perspective front view of a special

framing that is provided for guiding various denomination-selecting members and register-selecting elements. This figure also shows a portion of the connections to the carriage-returning train.

Figure 5 shows some of the mechanism seen at the rear portion of Figure 3, and illustrates the method of selecting a register.

Figure 6 illustrates the manner of fastening a distributing arm 67 to its rock-shaft 66.

Figure 7 is a sectional elevation of the mechanism seen at the rear of Figure 3, and shows the method of dropping the denomination jacks out of the path of their tappet.

Figure 7a shows the preferred provision of a roller at a point of breaking of the denomination-selecting rods.

Figure 8 is a rear perspective elevation of the denomination-selecting and register-selecting mechanism and paper-carriage.

Figure 9 is a front sectional elevation, showing the carriage being arrested at the tabulating operation, and showing the denomination jacks dropped for clearance.

Figure 10 is a sectional front elevation, showing a register-selecting cam-plate depressed by the blade provided upon the paper-carriage.

Figure 11 is a front sectional elevation, showing how the denomination jack is depressed and held down by the carriage-tappet.

Figure 12 is a rear sectional elevation, showing divergent register-selecting trains.

Figure 13 is a perspective rear view of a combination device, including a tabulating stop, a denomination tappet and a register-selecting block with teeth adjusted therein.

Figure 14 is a perspective rear view of the transverse denominational rock-shafts, the pin-bars set forward thereby and also the register-selecting elements in Figure 12.

Figure 15 is a sectional elevation of parts seen at the rear portion of Figure 3, showing the disconnection or breaking of the register-selecting trains, etc.

Numeral-keys 20 depress levers 21, which vibrate bell-cranks 22 and swing type-bars 23 up against a platen 24.

The platen is mounted upon a platen-frame 25 that is shiftable up and down upon a carriage 26, traveling upon rails 27, 28. The carriage has a letter-space rack 29 to operate the usual escapement-wheel train, which is represented by a pinion 30. As usual the escapement movements of said train are controlled by a universal bar (not shown) that is operated by heels 31 on the type-bars.

From the numeral-type-key depend indexing links 32 to depress arms 33 upon horizontal rear-wardly-extending rock-shafts 34. Each rock-shaft has an arm 35, to which is pivoted a transverse horizontal rod 36, forming part of a parallel motion which also includes a transverse horizontal bar 37 beneath rock-shafts 34. These bars 37 are depressed at the strokes of the keys.

Said bars 37 selectively depress index pins or members 38. These pins project from the top edges of bars 39, there being one pin on each bar 39 for each depressor-bar 37. There is one index-pin-bar for every dial in each register 40, there being five groups of pin-bars indicated at Figure 14, for the five registers, although there may be either more or less than five. The pin-bars have on their forward ends racks 41 to operate pinions 42 which drive the dials by means of pawls 43 and ratchets 44, as usual.

Upon the operation of any key the type-bar is swung to the platen to print, and its linkage 36, 37 presses down a corresponding index-pin 38. The pin-bars are normally retracted, so that the pins are normally inoperable by the bars 37, but, by means which will presently be described, the pin-bars 39 are advanced, one denomination after another, by the action of the paper-carriage 26, so that all the pins in one denomination will take 10 positions under the depressible setting bars 37. The indexing or setting of a pin causes it to protrude from the bottom of the bar 39, into the path of a general operator 45, which duly advances and engages all of the set pins for the purpose of driving the dials as usual.

The paper-carriage is driven by the usual spring barrel 46, Figure 5, with sufficient force to enable it to advance five pin-bars 39, one for each of the five registers; and this happens at 20 every step of the carriage in each computing zone. Feeding dogs which control the movements of the escapement-wheel 47 in said Figure 5 are not shown, but they have the usual operation, to feed the carriage through the computing zone.

25 For setting forward the index-pin-bars 39 seriatim, there is provided upon the paper-carriage one or more denomination-selecting tappets 48, Figure 13, each in the form of a cam, which depress one after another denomination 30 bevel-top jacks 49, forming a row at the rear of the typewriting machine. Each tappet 48 is universal to all the denomination-trains. Only a single tappet is in use while the computing zone is being traversed by the carriage. A single tappet 35 is used for each zone. Thus the tappets operate one at a time. As many tappets 48 may be employed as desired; and they may be adjustably carried upon racks 50, 51 mounted upon the carriage 26, as will presently be explained. The 40 action of a tappet in depressing the jack is seen at Figure 11. The jacks are in the form of vertical slides, guided at their upper ends in slots 52 formed in a horizontal plate 53 fixed upon the machine-framing. At their lower ends the jacks 45 are formed with stems 54 that work in guide-holes 55, forming a row in a fixed guide-plate 56, Figure 4.

The bottom of each denomination-jack engages the top of a vertical rod 57 to press it down. 50 These rods, forming a transverse row, are guided at their upper ends in holes 58 in guide-plate 56, Figure 4, and have upon their lower ends vertically-adjustable heads 59, into which the lower ends of the rods are threaded and secured by 55 screws 60, Figure 3. The heads 59 are guided in holes 61 in a horizontal transverse plate 62, Figures 3 and 4.

Said rod-heads 59 engage the tops of a row of upstanding links 63, pivoted at their lower ends 60 at 64 to horizontal rock-arms 65 fastened upon horizontal transverse denominational rock-shafts 66. From each of these rock-shafts ramify pendent distributing arms 67, whose lower ends are pivoted to forwardly-extending couplers 68 that 65 cause the index-pin-bars 39 one by one to take advanced positions preparatory to digit-indexing. This takes place in any one or more selected groups, as the carriage steps through the computing zone. The method of selecting the groups will 70 presently be explained. A corresponding index-pin-bar 39 is set forward by each train operated by the beveled tappet 48 and including coupler 68.

A part 57 taken with 63 forms a jointed thrust-bar 75 operable by its jack 49, and connected at its

lower end to depress an arm 66. This thrust-bar is made in two parts, so as to permit separation of 57 from 63 when required, as will be explained. The upper ends of the links 63 are guided in a comb 69, Figures 1, 7 and 8, and after depression they are returned by springs 70.

Inasmuch as the paper-carriage 26 travels from left to right, and the digit of highest denomination being typed first, it follows that the denominational order of the jacks 49 is inverted; and the same is also true of the denominational train-elements 51, 63 and 66. At Figure 14, the uppermost arm 65 and shaft 66 are of lowest denomination. Upon the next lower rock-shaft 66 the arm 65 is placed at the left, viewed from the rear. Upon the shaft under that, the arm 65 is placed still more to the left, and so on, at Figure 14. But upon the set of rock-shafts 66 the arms 67 have a transposed arrangement, the arm 67 on top shaft 66 having an extreme leftward position (viewed from the rear at Figure 14), the next lower arm 67 being placed at the right, and so on through each set of arms 67.

It will be seen that the denominational order of the arms 67 in each group is normal. Each group of distributing arms 67 forms a diagonal row extending downwardly from left to right at Figure 14. The extreme left-hand arm 67 at Figure 14 has lowest denomination; the next lower arm has the next higher denomination, and so on. This arrangement gives the distributive pin-bar-setting arms 67 the required order, without the interposition of the transposition mechanism.

The denomination-rock-shafts 66 are arranged in a row or tier, which extends upwardly and forwardly, whereby it is contrived to have the lower ends of distributing arms 67, which have graduated lengths, terminate about on a level, so that the couplers 68 may occupy a horizontal row; while the rear ends of master-arms 65, also graduated in length, terminate in nearly a vertical transverse plane, so that the train-elements 51, 63 may form transverse rows. By the diagonal arrangement of the rock-shafts, and by the graduation of the lengths of the arms 65, 67, equal movements of the jacks 49 are caused to produce equal advance movements of the index-pin-bars 39, since the proportions of arms 67 to arms 65 are maintained throughout the system. Thus the graduation of the arm-lengths, with the diagonal arrangement of the tier of shafts, permits arrangement of the couplers 68 in a single level row, and also permits the rods 57 and 63 to form a single transverse row.

Each transverse denominational rock-shaft 66 extends entirely across the machine, and five pendent distributive arms 67 branch therefrom, one arm for each computing register, the arms 67 forming five groups in a transverse row. It results that each denominational train 49, 51, 63, 65, 66, through its five branches 67, controls five pin-bars 39, one in each group, so that the stepping of the paper-carriage 26 causes all five pin-bars to be displaced or set forwardly to digit-indexing positions. Each denominational train extending down from the paper-carriage 26 therefore answers for all five of the registers.

For supporting the rock-shafts 66 against springing, and for facilitating assembly and disassembly, there may be erected end brackets 71, 72, Figure 14, and spaced brackets 73, the latter intervening between the groups of pendent distributing arms 67. All of the brackets may be erected upon a base-plate 74; each bracket hav-

ing feet 75 fastened down by screws 76. The intervening brackets 73 have open diagonal slots 77 in which the shafts may be detachably seated; and the end brackets may have holes 78 into which the ends of the shafts 66 are thrust. The brackets 71, 72 are provided with confining plates 79 covering and confining the ends of the rock-shafts 66, and detachably secured by screws 80, whereby displacement of the shaft is prevented and convenient detachment thereof is permitted; while the plate 74, with its brackets and shafts, together with the arms thereon, may be constructed as a unit for fastening down upon a platform 81 that forms part of the adding-machine base 82 upon which the typewriting machine stands. The brackets may all be connected and supported by a front tie-rod 83, fastened to ears on each bracket by screws 84.

The couplers 68 may thrust against shoulders 85 formed on the pin-bars 39 at the rear thereof. Normally all of the couplers 68 lie depressed, and hence they are moved forward idly seriatim as the carriage 26 traverses the computing zone. The tips of the depressed thrust-links (Figure 15) pass idly under the shoulders 85 or 86.

For the purpose of bringing the sets of couplers 68 into use and thereby selecting the registers appropriate to each computing zone, each set is provided with a lifting and depressing yoke, including a transverse bar 87 having guide-holes 88 to lift and lower the couplers. These yokes or bars 87 have pairs of rearwardly-bent arms 89 to form bails, the bails being similar to one another and arranged in a row across the machine. The bails are pivoted at 90 to brackets 71, 72, 73, and also to supports 109, fastened on the base-plate 74.

Each yoke 87, 89 is universal to its set of couplers 68, and forms part of a register-selecting train that extends to the paper-carriage, whereby the latter is enabled to lift the couplers 68 into effective positions in any one or more selected sets, and to maintain the couplers elevated throughout the traverse of the computing zone by the paper-carriage.

At the upper end of each register-selecting train is a cam-plate 93, which is in the path of a register-selecting blade or tooth 94 carried by the paper-carriage 26. There are shown five of the register-selecting cams 93, one for each register. They correspond with the five coupler-setting bails 87, 89. Any one or more of the five cams 93 may be depressed and held down by the carriage throughout its traverse of the computing zone, and the corresponding register or registers thereby brought into use.

Each register-selecting train includes a carriage-operated cam or cam-plate 93, and a thrust-rod 95 that extends down from the cam-plate and has at its lower end a head 96, which rests upon the top of a vertical link 97. The lower end of the link is detachably pivoted to the rear end of an arm 98, the latter connected to a forward arm 99. The arms are supported some upon a transverse shaft 100, and some upon shaft 108, these shafts being mounted end to end in the rear ends of middle brackets or supports 73, 109.

The forwardly-extending arms 99 are connected by links 101 to bail-arms 89, to lift the same and hold them elevated while the carriage passes through the zone. The set of downwardly-thrusting links 97 forms a row at the middle of the machine; while the bails 87, 89 form a row extending preferably the entire width of the ma-

chine. The lever-arms 98, 99 have a divergent relation, the arms 98 being compactly placed side by side just in front of the links 97, while the arms 99 are disposed at widely-separated points across the machine.

At Figure 12 the first register-selecting thrust-link 97 is pivoted to an arm 98, and the latter is bent to form a cross-bar 102 terminating in an arm 99, forming a bail; thus locating said arm 99 properly with respect to the middle of the five registers at Figure 14.

The second register-selecting thrust-link 97 at Figure 12 is connected by a cross-bar 103 to its arm 99, forming a bail within which is nested the just-mentioned bail 98, 99, 102; both bails 15 being loose upon the rock-shaft 100, so that either can turn independently thereof. The bail 103 is in position to lift the coupler-carrying bail 87, 89 for the second register at Figure 14.

The third thrust-link 97 at Figure 12 is connected to an arm 98 that is provided with a hub 104 which is secured by a set-screw 105 to the rock-shaft 100. The latter is supported at one end in a bracket 73, and it is also supported in arms 106 that extend rearwardly from supports 109. The rock-shaft 100 is operable independently of the bails which are loosely mounted thereon, and upon its outer end is fastened one of the arms 99, whereby it is connected to the left-hand bail 87, 89, to lift and lower the first 30 set of couplers 68, at Figure 14.

The fourth thrust-link 97 at Figure 12 is connected by a hub 107 to the rock-shaft 108, which is independent of 100, but is in line therewith, and is supported in arms 106 on the two right-hand supports 109, and also in middle bracket 73. A forwardly-extending arm 99 is fixed to the right-hand end of said rock-shaft 108, Figure 14, and extends forwardly and is connected by a link 101 to the extreme right-hand bail 87.

The extreme right-hand thrust-link 97 at Figure 12 is connected to an arm 98 that is connected by a cross-bar 110 to a forwardly-extending arm 99, the latter connected by a link 101 to the next to the last bail 87 at the right-hand portion of Figure 14. Hence, any coupler-bail 87 may be lifted or lowered independently of the others, under the control of the paper-carriage.

The transverse register-selecting cam-plates 93 are parallel and arranged on edge one behind another at the rear of the typewriter, and may be used selectively by the aid of the attachable blades or teeth 94 which fit into notches or seats 111, the latter forming a row in the under side of a block 112, that extends rearwardly from the denomination-selecting tappet 48. A register-selecting blade or tooth 94 is inserted in any notch 111, to predetermine the register that is to be brought into use. Two or more teeth 94 may be used simultaneously, so that any number 60 of the registers may be brought into use while the typing is being done in any column on the work-sheet.

These teeth 94 are short and fit closely in the notches 111, and are held by a securing pin 113 65 that is threaded at its end at 114 and screwed into a threaded hole in the forward end of the block 112, and will not work loose. Each of the register-selecting teeth 94 has beveled corners 115, and each cam-plate 93 has similarly-beveled top corners 116, to enable the tooth to cam down the cam-plate 93. These cam-plates are guided in upper and lower pairs of racks 117, 118.

In the organization of the machine, the above-described set of column-selecting vertical rods 75

is arranged at the back of the set of vertical denomination-determining master-rods 57, and the latter are placed back of the usual Underwood vertical decimal-tabulator plungers or stops 119, which are disclosed in the McLaughlin Patent 956,114, of April 26, 1910, and also in said patent to Hart, which also shows various features of the indexing devices, registers, and other computing mechanism, of the well-known Underwood machine, upon which the present invention includes improvements.

The decimal-tabulator vertical plungers or stops 119 are disposed at letter-space intervals, to co-operate with column-stops 120 mounted 15 adjustably upon the carriage 26. The column-stop-device 120 is forked to fit upon rack 50; the bottom part of the device consisting of the column-stop proper, and the upper part catching over the top of the rack. The decimal-stops 119 20 are operated by keys 121 and levers 122, whose rear ends lift the plungers or stops 119.

Each column-stop 120 is preferably provided 25 with a denomination-selecting tappet 48 for the adding and indexing mechanism, and also with a block 112 for the register-selecting mechanism. The column-stop, the denomination-selector and the register-selector may be united and form a unit, Figure 13, which may be adjusted along the carriage to correspond with the position 30 upon the work-sheet of the column in which the typed numbers are to be added. The carriage 26 is arrested by the column-stop in position for the depression by tappet 48 of the selected denomination-train 49, etc., and the register-selecting cam-plate 93 is depressed by the blade 94.

Each block 112 has upon its top a steadyin fin 123 to fit in a notch in the bottom of the supporting rack 51. The tabulator plungers or stops 119 are mounted in a vertical frame 124, resembling the usual Underwood frame seen in said 40 patents. This tabulating-stop-frame 124 is secured to the rear wall 125 of the main typewriter-frame 125, Figure 3.

The register-selecting cam-plates 93 are confined face to face and mounted upon opposite vertical walls 126, 127, which carry the slotted guides 117, 118 for said cam-plates 93. Said vertical walls 126, 127 rest upon a cross-member 128, to which they are secured. Said cross-member is formed as at 260^a to clear the rods 95 and has forwardly-extending end arms 129 which are fastened at 130 to a plate 131, the latter being detachably fastened across the back of the decimal-tabulator-frame 124.

The upper portions of the walls 126, 127 are provided with angular brackets 132, Figure 4, which are detachably fastened to posts 135, which are secured by screws 136 to the cap-plate 53, which is held by screws 138 upon the top of the tabulator-frame 124. The plate has notches 139 along its front edge to match notches 140, the latter formed upon the rear edge of a plate 141, secured by screws 142 to the top of the tabulator-frame 124; the front and top notches co-operating 60 to guide the vertical tabulator-stops 119.

Said cap-plate 53 is provided at its rear edge with a set of parallel guide-notches 52 for guiding the upper ends of the denominational jacks 49; and the latter are confined by a detachable plate 143, screwed to the rear faces of the posts 135. Each jack is provided with a shoulder 144 beneath the cap-plate 53, to limit the upward play of the jack.

It will be seen at Figure 4 that the plate 143 75 surmounts the detachable brackets 132, and the

main walls 126, 127 rise nearly to the top of the plate 143.

The upper ends of the register-selecting rods 95 are guided by holes in a plate or flange 145 that is bent forwardly from vertical plate 146, 5 which is detachably secured by screws 147 upon the rear edges of the side walls 126, 127.

It is desired that the register-selecting rods 95 stand side by side, to form a straight transverse row at their lower ends; while at their upper ends 10 they are operable respectively by the several register-selecting cam-plates 93, which are placed one behind another. In consequence the rods 95 are given an echelon arrangement at their upper ends, the guiding holes in the plate 145 being so 15 arranged.

The cam-plates 93 are detachable and interchangeable, and are so guided for vertical movement that any of them is capable of thrusting down its associated rod 95 without binding the 20 cam-plate. To give the cams long bearings for this purpose, each cam is provided with a pair of downward guiding extensions or stems 148, fitting in the lower guide-comb 118, the stems extending down below the working or rod-engaging lower edges of the cam-plates 93.

For a steadyng device or support the upper end of the plate 146 is bent forwardly, making a key 146^a that extends the width of the computing zone. It is so placed that it will enter 30 slots 149 that are provided upon the rear ends of the register-selecting blocks 112. This insures the proper engagement and accurate co-operation of the teeth 94 with the cam-plates 93, and of the tappets with the jacks, but without binding the paper-carriage 26.

It will be seen that the racks 50 and 51 extend between and are mounted upon arms 150, 151, Figure 8, that project rearwardly from the rear bar 159 of paper-carriage 26.

The rack-bar 51 may be adjusted endwise, being secured at its ends by nuts 160 upon eccentric studs 161 rising from rotatable bosses 162, that are secured by screws 163 upon the rear ends of the arms 150, 151. The bar 51 may be shifted endwise as far as is necessary, when the screws 163 have been loosened, and the bar may be fastened in position by tightening the screws 163. The ends of the rack 50 are held down upon the arms 150, 151 by means of nuts 164 threaded upon the tops of studs which rise from said arms. There is provided at Figure 8 a scale 165 by which to set the tabulating, denomination-selecting and register-selecting combinations. The scale is adjustably supported by slotted ears 166, carried by the same studs as nuts 164. The ears are held down by the nuts.

In operation, after the work-sheet is passed around the platen 24, the scale 165 is utilized in setting the combined column-stops, denomination-selectors and register-selecting blocks 120, 48, 112 along the racks 50, 51. Each column-stop may have one or more register-selecting blades 94, and these may be placed in any selected notch 111 on the block 112 to determine which register or registers are to be operated in each column or zone for which the block is set. In setting the selected blades 94, the operator may be aided by the numbering of the notches 111 which appears at Figure 13.

The keys 20, 161 are operated to type the date and other data; and then a tabulator-key 121 may thrust up a decimal-stop 119, releasing the paper-carriage by means of a universal bar 168, which is operable by shoulders 169 on the decli-

mal-stops 119. The universal bar 168, by means of the usual link 170, rocks a lever 171, on the front end of which is a roll 172, that lifts the carriage-rack 29 from the pinion 30 that is connected to the usual escapement-wheel 47. The carriage 26 is shown at Figure 7 in released condition.

The carriage then runs under the tension of its driving spring barrel 46, until the first column-stop 120 engages that decimal-stop 119 which was projected by the key 121. The operator releases the key 121, and the stop 119 is returned by its spring 175; while the carriage is restored to the control of pinion 30 and escapement-wheel 47. The machine is now ready for typing and computing the first number.

By this time the register-selecting tooth or teeth 94 have depressed the appropriate register-selecting cam plate or plates 93; this depression having been effected during the final operation of the tabulating movement of the carriage just described. Accordingly one or more rods 95 are depressed, to carry down certain of the links 97 and vibrate the corresponding lever-arms 98, 99, 25 to swing up the connected bails 87, 89, to lift the selected sets of horizontal couplers 68 to effective positions behind the heels or shoulders 85, 86 on the pin-bars 39. This is preparatory to typing the number upon the work-sheet. When the 30 number is typed, the digit-pins will be set accordingly for the selected registers. As each type-key is depressed, it presses down the lever 21 and vibrates forwardly the bell-crank 22, and swings the type-bar 23 upwardly and rearwardly 35 to strike against the work-sheet on the platen; the shoulder 31 on the type-bar operating the usual universal bar (not shown) to control the carriage-escapement-wheel 47.

In typing the number, as each numeral-type-key 20 is depressed, its link 32 depresses arm 33 and rocks the rock-shaft 34, of which one is provided for every numeral-key.

The arm 35 is rocked and thrusts endwise the horizontal transverse link 36 of the pin-setting linkage, thereby depressing the corresponding transverse bar 37 of the same linkage, for the purpose of depressing the index-pin 38 (Figures 8, 15) that the selected key 20 indicates.

It will be perceived at Figure 3 that the transverse bar 37 normally stood above the spaces between the pins 38; but it will be understood that upon the conclusion of the described carriage-movement, the tappet 48 operated the proper denomination-train and advanced the pin-bar 39, 55 so that during the operation of said numeral-type-key 20, said pin-bar stands in an advanced or forward position, with all of its pins directly under the bars 37.

It will be seen at Figure 13 that the dog 48 has broad camming surfaces, and it will also be seen at Figure 11 that the tips 176 of the jacks 49 are beveled correspondingly, so that the carriage meets with but little resistance in camming down the jacks 49 as the carriage proceeds step by step.

At Figure 11 is shown the one of the jacks held depressed while the carriage stands in the described typing position. By the depression of the jack 49, the link 57 is thrust down together with link 63, arm 65 is depressed, rock-shaft 66 is rocked, and arm 67 is swung forwardly together with the elevated coupler 68, thereby thrusting forward the pin-bar 39, together with the index-pins 38 thereon, the entire train remaining in this operated condition as long as the carriage 75 remains stationary. Hence by depression of the

key 20, the digit is printed and the index-pin 38 is set.

It will be perceived further that at the just-described operation an index-pin 38 may be set for each of several selected registers, depending upon how many register-selecting teeth 94 have been placed in the first adjustable block 112, and what positions these teeth occupy in the notches 111 in said block. If there are several teeth 94 in place, then several of the cam-plates 93 are depressed, and several register-selecting trains are in effective positions, and consequently there are several of the pin-bars 39 set forwardly, one for each register.

The forwardly-displaced pin-bars are of the same denomination in all selected registers, so that there are as many pins 38 selected and depressed in the desired denomination as there are register-selecting trains brought into use at the time by the teeth 94 in the block 112.

At the completion of any carriage movement at any point in the computing zone, the pin-bar-setting cam 48 depresses a jack 49, and, by means of the links 57, 63 and arm 65, the corresponding rock-shaft 66 is rocked, and five branching arms 67 are rocked forwardly, operating five couplers 68. Some of these couplers may move idly, but the others, being under the control of the register-selecting teeth 94 and hence being in elevated positions, are thrust forward effectively, to advance the pin-bars 39 against the tension of springs 177, thus bringing the pins 38 to setting positions, where they remain as long as the carriage remains stationary.

Upon the relief of the numeral-key 20 from pressure, the type-bar 23 swings back to normal position, and the carriage 26 is permitted to escape and feed for a letter-space distance. The denomination-selecting dog 48 releases the jack 49, and springs 70 lift the links 57, 63, and restore the arms 65 and rock-shafts, together with the arms 67, pendent from said rock-shafts, and thus carrying backwardly the projected couplers 68 and permitting the springs 177 to return the pin-bars 39 to normal positions, together with both set and unset pins 38 thereon.

It will be understood, however, that the register-selecting trains will remain set under the control of the blades 94, and that said trains will continue set throughout the computing zone, or as long as said teeth 94 ride upon the top edges of the register-selecting cam-plates 93, Figure 10.

During the letter-feeding movement of the carriage to the left from one denomination to the next, just referred to, the cam 48 engages and depresses the succeeding jack 49, and, by means of the jack-train, thrusts forwardly the next pin-bar 39 on the right, or of next lower denomination; so that when another digit-key 20 is operated, the transverse setting bar 37, that is connected to said key, depresses a pin 38 in each of the bars 39 that are set forward by the couplers 68 of the various distributing arms 67.

In this manner the typing and indexing proceed until the number is typed, whereupon the tooth or teeth 94 ride off from the register-selecting cam-plates 93.

After the typing of the number in the adding zone is completed, a general operator is brought into use, either by hand or by electric motor (operated by the usual key, not shown), said general operator including the usual cross-bar 45, which moves forwardly and engages all of the depressed pins 38, Figure 15, and thereby drives forwardly the pin-bars 39, causing the racks 41 on their

forward ends to rotate the pinions 42 and drive the dials 43; whereupon the general operator 45 returns, and, by means of the hardened lugs 86, restores the pin-bars 39 to normal positions.

5 Thereupon a tabulator-key 121 is depressed, and the carriage is released and runs until the projected stop 119 is arrested by the next column-stop 120, whereupon the described operation is repeated for typing, indexing and adding the 10 next number.

10 In the second adding zone, the desired register or registers are selected according to the setting of the tooth or teeth 94 in the notches 111 of the second combined column-stop, block and denomination-selector 112, 120, 48. Each column has its own combined stop and block; and the register-selection for the various columns may be all the same, or all dissimilar if desired, or one register may be operated in all the columns, while 15 20 a variety of registers are operated in some of the columns, and other registers in others, to accomplish any desired result. In this manner the typing and computing proceed until the line of writing is finished.

25 If desired, the carriage can be returned by hand. During the return of the carriage by hand, the denomination-selecting tappets 48 may ride back idly over the denomination-jacks 49, depressing them one after another, and operating 30 their trains idly. The register-selecting blades 94 in each block 112 may also engage the zone-cams 93 and depress them idly in the successive columns, together with their trains. It will be seen that if it is desired at any time to 35 step the carriage back to any point to correct an error, the selecting tappet 48 will, at the desired point, depress and hold down the denominational-train, while the tooth or teeth 94 will depress and hold down the desired register-selecting trains.

40 It is preferred, however, in practical use, to return the carriage by means of a motor-key 179, with means controlled by said key for clearing the denominational tappets 48 as they pass through the successive adding zones. Depression of the 45 carriage-return key 179 rocks a bell-crank 180, having an arm 181, Figure 3, the tip of which engages a nose 182, and thereby lifts a latch 183 free of a catch 184. This permits a spring 185 to snap or engage latch 183 rearwardly, thereby 50 vibrating an arm 186 and rocking a horizontal shaft 187. From said rock-shaft there is pendent an arm 188, to the lower end of which is attached the end of a switch 189, which is caused to close the circuit to the usual carriage-return motor (not shown). At the same time a clutch 190 is 55 closed, enabling the electric motor to drive a carriage-returning pinion 191 that meshes with carriage-rack 192. Hence the carriage is returned for beginning the typing of a new line.

60 The clearing of the denominational-tappets 48 is effected in the following manner at the return of the carriage:

Upon said rock-shaft 187 is fixed an arm 193, connected to a pull-link 194, which at its rear end is connected to another pull-link 195 that is pivoted to an arm 196 upon a rock-shaft 197, the latter having a horizontal arm 198, upon which is fixed a cam 199 to engage a pin 200 that is provided in the lower end of a bail which guides 70 the denominational master-links 57 at their lower ends.

75 This bail comprises a pair of arms 201, connected to their bottoms by horizontal cross-bar 62, the latter having the guiding slots 61 for the lower ends of heads 59. The depression of arm

198 cams the pin 200 forwardly together with the bail-arms 201, and the cross-bar 62 swings the lower ends of all of the upper rods 57 forwardly clear of the upper ends of the lower links 63. Hence when the denomination-tappet 48 rides over the jacks 49, it will not contact therewith, because the upper links 57 and the jacks have dropped, being no longer supported upon the tops of the links 63. Thus the carriage is returned at the beginning of the line without interference 10 from the jacks 49.

The heads 59 upon the links 57 may be adjusted by turning them up or down upon the threaded lower ends of the master-rods 57, and securing them by the screws 60, so that each will 15 have a proper contact with the top of its under link 63.

It will be understood that upon the completion of the carriage-return, the links 195, 194 and the arm 198 are restored by spring 202, thereby camming pin 200 rearwardly; and that the rods 57 and jacks 49 are lifted by reason of the camming reaction of the beveled lower tips 203 of the heads 59 upon the beveled tops 204 of the links 63, Figures 1 and 15.

Upon the paper-carriage is a motor disabling tappet 205, which is effective, upon the completion of the return of the carriage, to strike a cam 206, Figure 3, in the usual manner, to vibrate a rock-shaft 207 and swing forwardly an arm 208, and thereby, by means of links 209, 210, to rock forwardly an arm 211 on horizontal rock-shaft 212. This operates to release arm 213 and unclutch 190 in the usual manner. An arm 214, pendent from the rock-shaft 212, at the same time swings rearwardly, and, by means of a link 215 and arm 216, rocks the shaft 187 to open the switch 189 in the usual manner. The latch 183 is thrust forward by the rock-arm 186, and the nose 182 rides idly over the top of the operating arm 181, being pivoted. The latch 183 catches again upon the catch 184 as usual. (See Hart Patent 1,238,908.)

It is also customary for the carriage, when completing its run in letter-feeding direction, to start the carriage-returning motor automatically, and there is usually provided for this purpose a part 217 which thrusts down a link 218 and vibrates a lever 219, lifting the latch 183 by means of a pin 220 thereon, to permit switch 189 to be closed and the clutch 190 to be also closed.

The foregoing disconnecting link 195 is pivoted at its forward end by a pin-and-slot connection 221 to the upper end of an arm 222, which is rigid upon the rock-shaft 223 of the tabulator universal bar 168, so that every time that the carriage is released for tabulating purposes, the rods 57 are disconnected from the links 63, so that the rods 57 and the jacks 49 may drop out of the path of the advancing denominational-selecting dogs 48 at the carriage-tabulating operation.

Since the digit-type-bars 23 carry also character-types which are brought into use by an upward shift of the platen 24 and its frame 25, it is provided that no computation shall take place when the special characters are being printed by the digit-type-bars. This silencing of the adding mechanism is secured by breaking the denominational-selecting trains at the operation of the case-shift mechanism. The platen-frame 25 has a roll 224 that runs upon an up and down shiftable rail 225, mounted upon a frame 226 that rocks upon a transverse shaft 221. Fixed upon said shaft and extending rearwardly there-

from is an arm 228, Figure 4, which, by means of a pendant link 229, depresses the cam-arms 198 to swing forwardly the frame 201, 62 to swing rods 57 forwardly clear of the links 63, so that 5 the denomination-selecting trains are not operated, nor the pin-bars 39 set forward, while said upper-case types are being printed.

The arm 228 may be adjustable for length, so as to make it feasible to secure the correct 10 operation of the link 229. Said arm 228 is fastened by screws 230 to a block 231 that is rigidly fixed to the rock-shaft 227 by means of a yoke 232 thereon. The screws 230 pass through slots 233 in the arm to permit endwise adjustment of 15 the latter. The lower end of the link 228 is slotted at 234 to permit the motion of the arm independently of the link 229 at certain operations of the arm.

The upper ends of the pendant arms 201 are 20 pivoted at 235 to ears 236 bent down from fixed plates 237 underlying the plate 56. The side arms 201 are additionally joined by cross-bars 238, so that precision of movement of the links 57 forwardly and backwardly is assured, and the 25 lower ends thereof are normally maintained in accurate relationship to the tips of the links 63.

Said returning springs 70 for the denomination-trains lift up the links 63, and rock the arm 65 and the rock-shaft 66 as far as they can go, 30 that is, until they are arrested by means of stops 239 formed upon the denomination-couplers 68, and pulled by the springs 70 back against a stop in the form of a cross-bar 240 joining the ball-arms 89 of the middle ball only. These 35 stops 239 may be pressed out from material of the couplers 68, or otherwise.

These stops 239, Figures 3, 5, 7, 15, are provided upon all of the couplers 68 in the system, and in all cases serve to prevent the couplers from 40 advancing too far, especially when they are depressed and advancing idly, as at Figure 15. These stops 239 encounter the front bars 87 of the bails, which prevent the idling couplers 68 from advancing so far as to lie directly beneath 45 the shoulders 85, Figure 15. Hence it is rendered impossible for the depression of a register-selecting cam-plate 93 to become blocked on its downward movement. Should a coupler 68 be in the Figure 15, position at the time that any 50 zone-cam 93 is being depressed, the bail 89 will rise, together with the couplers thereon, and any selected pin-bar 39 will be cammed forwardly, the rear corner of its shoulder 85 or 86 being beveled, as at 241, for this camming motion. The 55 coupler may be correspondingly beveled, as shown at Figure 5.

The arms 67, at Figure 6, may be secured to the rock-shafts 66 by the method of forming a spherical depression or seat at a spot in the rock-shaft and setting a ball 242 in the seat. The arm fits upon the rock-shaft, but has a notched projecting portion 243, so that the ball interlocks with the arm and the rod. Said notch is originally oversize, so as to permit the ball to be inserted in the seat. After the ball is in place the projecting part 243 may be pinched, to lock the ball permanently in position in the seat, and to secure enough friction to prevent the arm from slipping along the rock-shaft. This can 65 be done by pliers 244. If desired to further increase the rigidity of the arm 67 on the shaft 66, a drop of solder may be fixed around the shaft 66 and ball 242 at each side of the arm 67.

After the conclusion of the setting of pins 38 70 and the starting of the cycling of the general 75

operator, there is no further reason for the register-selecting balls 87, 88 to remain elevated, and provision is made whereby the general operator depresses all of said balls and insures that the couplers 68 shall be dropped to idle positions. Connected to the general operator to be rotated thereby is a cam-disk 245, having a V-notch 246 in which normally rests a roller 247. The general operator 45 is reciprocated by means of the usual racks, see the aforesaid Hart Patent 1,190,171. As seen in Figure 1, there may mesh with one of said reciprocated racks 282 a gear 283 fastened to a shaft 284, to which the cam-disk 245 is also fastened. The shaft 284 may be journaled at one end in the side of the adding-machine base 82, the other end being journaled in a bracket (not shown) rising from the platform 81. The gear is sufficiently large to rotate the shaft 284, and hence the cam-disk 245, in less than a complete revolution during the 20 movement of the general-operator rack 282 in either direction, thereby providing that the roller 247 may only be entered in the notch 246 when the general operator 45 is in its normal position.

At the cycling of the general operator, the disk 25 245 moves and the roller 247 is forced out of the notch, swinging rearwardly arm 248 provided upon rock-shaft 249; and upon the latter is an arm 248a, which, as seen in Figure 1, by means of a link 250, vibrates rearwardly a frame 251, 30 which is hinged at its bottom end at 252. This frame 251 includes a cross-plate 253 joining the side arms of the frame 251, and has at its top a rearwardly-bent flange provided with a comb 254 for the upper ends of the standing links 97, 35 said links being retained by a comb-plate 255, Figure 8. When the frame 251 is swung rearwardly, all of the links 97 are swung away from the links 95, and all of the cam-plates 93 drop.

At the same time cross-bar 253, which connects arms 257 of said swing frame 251, swings up under the arms 98 of the register-selecting frames and lifts said arms 98, thereby dropping the arms 98, together with all the elevated balls 87, 89 and the couplers 68 controlled thereby. 40 The balls may rest upon blocks 257a, Figure 15.

Such swinging back of the links 97 at this time is provided for, so that in case any zone-cam 93 should be held depressed by a block 112 at the moment, all of the links 97 will nevertheless 50 be free to rise when the cross-bar 253 lifts the arms 98 that carry said links 97. Furthermore the swinging back of the links 97 causes the zone cams 93 to drop clear of the teeth 84, thus facilitating a carriage return or tabulating move- 55 ment in case the latter occurs during cycling.

The coupling bails 87, 89 remain depressed throughout the remainder of the cycling of the general operator, and if the cycling occurs just after the carriage has left a computing zone, until 60 the paper-carriage 26 advances to a new computing zone when the bails required for said new zone will be raised. During the final portion of the cycling of the general operator, a spring 258 may return arm 248 and restore roller 247 to 65 the notch 246 as the latter returns to its normal position, and the link 250 will consequently return to normal position with the frame 251, 253, 257.

Springs 259, Figure 8, one on each side of a 70 cross-plate 253a of the vertical swinging frame 251, may restore the latter to normal position, bringing the links 97 forwardly, and by acting upon cams 260 upon the adjustable heads 96 carried by the bottom ends of the thrust rods 95, 75

may cam all of the latter upwardly. If, however, the carriage has not yet left the computing zone, and one or more of the zone-cams 83 still remain depressed, the springs 258 may become effective upon the movement of the carriage out of the present computing zone, whereupon the register-selecting blade or tooth 84 will escape from the depressed cam-plate 83, and the springs 258 will cam upwardly to normal positions the rods 85 together with the depressed cam-plates 83. If, however, a blade 84 should happen to be in effective position, the plate 83 cannot be raised, but the springs 258 may react to cam down idly the links 81 temporarily, lifting the bails 87.

15 The typewriting machine 125 can be lifted off from the adding-machine base 82, upon which it is located by means of studs 263, and held down by removable screw-clamps 264, Figure 3. In lifting the typewriting machine, the rods 85 and 20 87 lift off from the lower links 81, 83, and the operating key-links 82 lift away from the arms 83, so that all the lines of connection between the typewriter and the adding machine are self-disconnecting; and upon restoring the typewriting 25 machine, the studs 263 serve to relocate the parts 83, 87, 82 relatively to the related adding mechanism.

30 The top ends of the standing rods 87 may be provided with rolls 265, Figure 7^a, for engaging the cams 260 on the zone-rods 85, to give ease in camming up the latter by the springs 258.

During the tabulating operation all of the jacks 49 are dropped, as at Figure 9, to clear the tappets 48. The jacks 49 all rise from the Figure 9 position to the Figure 11 position when the carriage is being re-engaged with its escapement-mechanism. At Figures 9 and 11 is illustrated the operation at the conclusion of a tabulating jump of the carriage. The carriage, which is 40 moving towards the left, is preliminarily arrested by the contact of column-stop 120 with the upwardly-projected decimal-stop 119, as seen at Figure 9. Upon restoration of the carriage to the control of its escapement-mechanism in the usual manner, the carriage advances again, having at this time a very slight movement towards the left. This movement is much less than the pitch of the jacks, i. e., less than a letter-space interval. At Figure 11 is indicated the position 45 of the carriage after it has made said slight movement, and has been restored to the control of the letter-feeding mechanism. At Figure 11 the position of the tappet 48 at this time is shown in full lines; but the position of said tappet is 50 also shown in dot-and-dash lines at Figure 11 to represent the tabulating or temporarily held position seen at Figure 9. At Figure 11, in moving from the dotted-line position to the full-line position, the tappet 48 cams down one of the 55 jacks 49 and comes to rest on the top 176 of the jack, where it is held during the subsequent 60 operation of the figure type-key.

Figure 10 represents the position reached by the register-selecting block 112 when the carriage is tabulated to the position seen at Figure 9. The cam-plate 83 is depressed by its blade 84 before the jacks 49 are restored from the Figure 9 position to the Figure 11 position.

It is usual in the Underwood bookkeeping machine (see patent to Hart 1,270,411) for key-locking stems 266 to co-operate with a transverse set of tumblers 267 to enable any digit-key to lock all of the remaining digit-keys against actuation. According to the present improvements, there is a connection from the arm 248^a that also

locks the digit-keys during the cycling operation. This connection includes a link 268, operating an arm 269 upon a rock-shaft 270. Also upon said rock-shaft is arranged an arm 271, having a pin-and-slot connection to the rear end of a link 272, 5 whose forward end is pivoted to an arm 273, having a toe or interponent 274 to spread or operate the transverse row of tumblers 267 to lock the keys. The arm 271 is yieldingly connected by a pull spring 275 to said link 272. Upon the restoration of the arm 248^a to normal position, the springs 258 and 271^a, Figure 1, restore the described key-locking train to normal position, Figure 3.

In practicing the present invention, there are 15 preferably left punctuation-spaces to separate the groups of numerals that form a number. At such punctuation-spaces jacks 49 may be omitted. It is preferred, however, to supply their places with key-locking jacks, which are similar 20 to the jacks 49, thus forming an unbroken row of jacks, as at Figure 8. The rod 87 that is operated by each key-locking jack thrusts down a key-locking rod 276, Figure 1; these rods 276 at their lower ends being connected to arms 277 that 25 are fixed upon the rock-shaft 270, carrying the key-lock operating arm 271. At every punctuation-space the digit-keys are hence locked against actuation.

The movements of the swinging frame 251 for 30 dropping the zone cams 83 are limited by means of a stop 251^a, Figure 8, playing in a slot in an arm 278 of a subframe or bracket, which includes also an opposite arm 279, Figure 8, these arms being connected by a cross-plate 280. Said 35 swinging frame 251 is arranged between said arms 278, 279. The vertical cross-plate 280 is formed at its top with a forward ledge 281, upon which is fastened the guide-comb 69 for the upper ends of the links 62.

Variations may be resorted to within the scope of the invention, and portions of the improvements may be used without others.

Having thus described my invention, I claim:

1. In a combined typewriting and computing machine having a carriage and a series of registers, each register having a group of index pin-bars, a set of horizontal denominational rock-shafts extending across the machine, distributing arms operated by said rock-shafts and arranged in groups, one set of arms for each set of pin-bars, each rock-shaft also having a single master-arm whereby it is operated, a row of connections for operating said master-arms, a carriage-tappet, jacks operable by said tappet 4 for actuating said connections, rock-shafts and pin-bars, preparatory to a digit-indexing operation, sets of couplers operable by said distributing arms, and means carried by the carriage to shift the sets of couplers into and out of use 6 selectively, each coupler being shiftable relatively to its pin-bar.

2. In a combined typewriting and computing machine having a carriage and a series of registers, each register having a group of index pin-bars, a set of denominational rock-shafts extending across the machine, distributing arms upon said rock-shafts and arranged in groups, one set of arms for each set of pin-bars, each rock-shaft also having a single master-arm 7 whereby it is operated, said master-arms at their rear ends forming a transverse row, a row of connections for operating said master-arms, a carriage-tappet, jacks operable by said tappet 7 for actuating said connections, rock-shafts and 7

pin-bars, preparatory to a digit-indexing operation, sets of couplers operable by said distributing arms, and means carried by the carriage to shift the sets of couplers into and out of use selectively, 5 said distributing arms being of graduated lengths, said rock-shafts arranged in an inclined transverse plane, and the master-arms being of graduated lengths, the distributing arms imparting equal movements to the index pin-bars.

10 3. In a combined typewriting and computing machine having a carriage and a series of registers, each register having a group of index pin-bars, a set of denominational rock-shafts extending across the machine, distributing arms 15 upon said rock-shafts and arranged in groups, one set of arms for each set of pin-bars, each rock-shaft also having a single master-arm whereby it is operated, connections for operating said master-arms, a carriage-tappet, jacks operable by said tappet for actuating said connections, rock-shafts and pin-bars, preparatory to a digit-indexing operation, each rock-shaft carrying one distributing arm for each register, normally disabled groups of couplers connected to 20 said distributing arms, a shifting device, and means upon the carriage to act upon said shifting device to bring any group of couplers into co-operation with its associated pin-bars.

4. In a combined typewriting and computing machine having a carriage and a series of registers, each register having a group of index pin-bars, a set of denominational rock-shafts extending across the machine, distributing arms upon said rock-shafts and arranged in groups, 35 one set of arms for each set of pin-bars, each rock-shaft also having a single master-arm whereby it is operated, connections for operating said master-arms, a carriage-tappet, jacks operable by said tappet for actuating said connections, rock-shafts and pin-bars, preparatory to a digit-indexing operation, groups of couplers normally lying depressed and passing under the rear ends of the pin-bars when operated, and a system of yokes for lifting and depressing 40 said couplers, each yoke including a transverse bar having guide-holes for the couplers, and also including arms forming a pivoted bail, each yoke being universal to its set of couplers and forming a part of a register-selecting train 45 extending to the carriage, and means on the carriage to operate the train to lift the group of couplers selectively into effective position, and to maintain the couplers elevated throughout the traverse of the computing zone by the carriage.

5. In a combined typewriting and computing machine having a traveling carriage, a series of registers and digit-indexing means, the combination of a row of jacks in the form of shouldered slides, means to guide said slides, and a tappet 55 mounted upon the carriage to displace the jacks seriatim, said machine having a stop-plate with guides for said slides, and the latter provided at their lower ends with stems, a plate having guide-holes for said stems, a row of rods operable by said jacks, means to guide the upper ends of the rods, adjustable heads upon the lower ends of the rods, means for guiding said heads, a row of links under said rods and compressible thereby, rock-arms to which the links are pivoted at their lower ends, rock-shafts to which 60 said rock-arms are individually fastened, distributing arms grouped upon said rock-shafts, index pin-bars forming groups, one group for each group of distributing arms, couplers pivoted 65 to the lower ends of said pendent distributing

arms for operating said index pin-bars preparatory to a digit-indexing operation, and means to bring the different sets of couplers into use selectively, whereby one pin-index bar in every group having the same denomination as the jack 5 may be set forward by the selected couplers.

6. In a combined typewriting and computing machine, the combination with a series of registers and a traveling carriage, of a tappet on the carriage, a set of denomination-selecting 10 jacks, a row of rods operable thereby, a set of transverse rock-shafts having master-arms operable by said rods, said rock-shafts having a downwardly and rearwardly inclined echelon formation, distributing arms of graduated 15 lengths, there being one distributing arm on each rock-shaft for each register, a set of index pin-bars for each register, groups of normally idle couplers forming a transverse row between the distributing arms and the pin-bars, the couplers 20 in each group being of graduated lengths, said master-arms being also of graduated lengths, the denominational order of the distributing arms being the reverse of the order of the master-arms, the lower ends of the distributing arms terminating about evenly, the proportions of the master-arms and distributing arms being maintained 25 throughout the system, and equal movements of the jacks producing equal advances of the index-pin bars, and means for bringing the groups of 30 couplers into use selectively.

7. In a combined typewriting and computing machine having a series of registers and a carriage, the combination of denomination-selecting jacks forming parts of trains each ramifying to 35 the different registers, register-selecting cam-plates, and a tabulator-mechanism including a column-stop on the carriage, said column-stop forming part of an adjustable unit which also includes a denomination-selecting tappet and a 40 register-selecting tooth, said unit and tooth being arranged for differential location of the tooth on the unit at will, the parts being arranged so that the carriage is arrested by the column-stop in position for operation of a denomination-jack by 45 the tappet and for the depression of the cam-plate selected by the tooth.

8. In a combined typewriting and computing machine having a series of registers and a carriage, the combination of denomination-selecting 50 jacks forming parts of trains each ramifying to the different registers, a stationary group of register-selecting cam-plates mounted face to face, racks upon the carriage, and elongate units each mounted on said racks and bridging the same, 55 each unit having a cam-plate operating tooth, and also having a column-stop device forked at one end to fit upon one rack, one part of the fork formed to enter the notches in its rack, and the other part catching over the top of the 60 same rack, each unit having a beveled denominational jack-selecting tappet between the column stop and the register-selecting tooth, said unit having locating means to engage the notches in the other rack, and having the column-stop, 65 the denominational jack-selecting tappet and the register-selecting tooth arranged along the bottom thereof, said other rack and the unit-locating means co-operating therewith being disposed at the top of said unit.

9. A device formed for adjustment along the carriage of a combined typewriting and computing machine, said device being in the form of an elongate structure and having on one elongate side a tabulating tooth, and also having on one 70

- side a denomination-selecting tappet, and also provided with notches to removably receive register-selecting teeth, said tappet being between the tabulating tooth and the notches.
5. 10. A device formed for adjustment along the carriage of a combined typewriting and computing machine, said device being in the form of an elongate structure and having on one elongate side a tabulating tooth, and also having on said side a denomination-selecting tappet, and also provided with notches to removably receive register-selecting teeth, a steadyng ridge being provided upon the side of said structure opposite said notches, to fit in the notches of a supporting rack on the typewriter-carriage.
10. 11. A unit formed for adjustment along the carriage of a combined typewriting and computing machine, said unit being in the form of an elongate structure and having on one elongate side a tabulating tooth, and also having on said side a denomination-selecting tappet, and also provided with notches to removably receive register-selecting teeth, a steadyng ridge being provided upon the side of said structure opposite said notches, to fit in the notches of a supporting rack on the typewriter-carriage, said unit also having a key-formation to fit upon a stationary guide in the vicinity of the computing zone of the machine.
15. 12. In a combined typewriting and computing machine having a series of registers and a carriage, the combination of denomination-selecting jacks forming parts of trains each ramifying to the different registers, register-selecting cam-plates, and a tabulator-mechanism including a column-stop on the carriage, said column-stop forming part of an adjustable unit which also includes a denomination-selecting tappet and a register-selecting tooth, the parts being arranged so that the carriage is arrested by the column-stop in position for operation of a denomination-jack by the tappet and for the depression of the selected cam-plate by the tooth, a fixed horizontal guide or key being mounted in proximity to the computing zone, each unit having a notch in its rear end which fits upon said key while the carriage is traversing the computing zone, to insure proper co-operation of the unit with the register-selecting cams and the denomination-jacks.
20. 13. In a combined typewriting and computing machine having registers, a carriage, tabulating mechanism and indexing mechanism, the combination of a key on said machine at the rear of said carriage, said key extending in the direction of the travel of the carriage, and a tabulating and denomination-selecting unit upon said carriage having a sliding fit upon said key to insure the proper engagement and accurate co-operation of the denomination-selecting unit with the jacks throughout the computing zone.
25. 14. A combined typewriting and computing machine having a computing base provided with registers, the typewriting machine detachably mounted upon the base, a set of carriage-controlled denomination trains descending from the carriage into the computing base, and including upper and lower combined sets of thrust rods, the upper rods being separable from the lower rods, a register-selecting set of trains extending down from the carriage into the computing base, and including upper and lower sets of rods, one set separable from the other, the separation of all of said rods permitting the typewriting machine to be lifted off from the computing base,
30. 15. In a combined typewriting and computing machine having a carriage and a series of registers, each register having a group of index-pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, each of said connections being made in portions, and automatic devices for separating one portion from the other to permit the jacks to drop out of the way of the carriage-tappet.
35. 16. In a combined typewriting and computing machine having a traveling carriage, a register and digit-indexing means, the combination of a row of jacks in the form of slides, means to guide said slides, a tappet upon the carriage to displace the slides seriatim, said slide-guiding means including an upper plate on the machine with guides for said slides, and the latter provided at their lower ends with stems, said guiding-means including a lower plate having guide-holes for said stems, a jointed thrust-rod operable by each jack, arms displaceable by said rods, each rod made in two parts to permit separation of the parts when required, means for maintaining the jointed ends of the rods in alignment and index pin-bars operable by said arms.
40. 17. In a combined typewriting and computing machine having a carriage and a series of registers, each register having a group of index pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, a base-plate, and brackets erected upon said base-plate at its ends, other brackets between its ends, said rock-shafts journaled in said brackets, the end brackets having holes for the rock-shafts and also having outside confining plates covering the ends of the rock-shafts, and the intervening brackets having open slots permitting detachment of the rock-shafts, each rock-shaft having a spherical depression or seat, and a ball fitted therein, and each rock-arm being pinched upon the ball and soldered.
45. 18. In a combined typewriting and computing machine having a carriage and a series of registers, each register having a group of index pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, a base-plate, and brackets erected upon said base-plate at its ends, other brackets between its ends, said rock-shafts journaled in said brackets, the end brackets having holes for the rock-shafts and also having outside confining plates covering the ends of the rock-shafts, and the intervening brackets having open slots permitting detachment of the rock-shafts, each rock-shaft having a spherical depression or seat, and a ball fitted therein, and each rock-arm being pinched upon the ball and soldered.
50. 19. In a combined typewriting and computing machine having a carriage and a series of registers, each register having a group of index pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, a base-plate, and brackets erected upon said base-plate at its ends, other brackets between its ends, said rock-shafts journaled in said brackets, the end brackets having holes for the rock-shafts and also having outside confining plates covering the ends of the rock-shafts, and the intervening brackets having open slots permitting detachment of the rock-shafts, each rock-shaft having a spherical depression or seat, and a ball fitted therein, and each rock-arm being pinched upon the ball and soldered.
55. 20. In a combined typewriting and computing machine having a carriage and a series of registers, each register having a group of index pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, a base-plate, and brackets erected upon said base-plate at its ends, other brackets between its ends, said rock-shafts journaled in said brackets, the end brackets having holes for the rock-shafts and also having outside confining plates covering the ends of the rock-shafts, and the intervening brackets having open slots permitting detachment of the rock-shafts, each rock-shaft having a spherical depression or seat, and a ball fitted therein, and each rock-arm being pinched upon the ball and soldered.
60. 21. In a combined typewriting and computing machine having a carriage and a series of registers, each register having a group of index pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, a base-plate, and brackets erected upon said base-plate at its ends, other brackets between its ends, said rock-shafts journaled in said brackets, the end brackets having holes for the rock-shafts and also having outside confining plates covering the ends of the rock-shafts, and the intervening brackets having open slots permitting detachment of the rock-shafts, each rock-shaft having a spherical depression or seat, and a ball fitted therein, and each rock-arm being pinched upon the ball and soldered.
65. 22. In a combined typewriting and computing machine having a carriage and a series of registers, each register having a group of index pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, a base-plate, and brackets erected upon said base-plate at its ends, other brackets between its ends, said rock-shafts journaled in said brackets, the end brackets having holes for the rock-shafts and also having outside confining plates covering the ends of the rock-shafts, and the intervening brackets having open slots permitting detachment of the rock-shafts, each rock-shaft having a spherical depression or seat, and a ball fitted therein, and each rock-arm being pinched upon the ball and soldered.
70. 23. In a combined typewriting and computing machine having a carriage and a series of registers, each register having a group of index pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, a base-plate, and brackets erected upon said base-plate at its ends, other brackets between its ends, said rock-shafts journaled in said brackets, the end brackets having holes for the rock-shafts and also having outside confining plates covering the ends of the rock-shafts, and the intervening brackets having open slots permitting detachment of the rock-shafts, each rock-shaft having a spherical depression or seat, and a ball fitted therein, and each rock-arm being pinched upon the ball and soldered.
75. 24. In a combined typewriting and computing machine having a carriage and a series of registers, each register having a group of index pin-bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, a base-plate, and brackets erected upon said base-plate at its ends, other brackets between its ends, said rock-shafts journaled in said brackets, the end brackets having holes for the rock-shafts and also having outside confining plates covering the ends of the rock-shafts, and the intervening brackets having open slots permitting detachment of the rock-shafts, each rock-shaft having a spherical depression or seat, and a ball fitted therein, and each rock-arm being pinched upon the ball and soldered.

bars, a set of horizontal denominational rock-shafts extending across the machine, a row of distributing arms depending from said rock-shafts and arranged in groups, one set of arms for each set of pin-bars, each rock-shaft also having a single rearwardly-extending master-arm whereby it is operated, said master-arms at their rear ends forming a transverse row, a row of connections for operating said master-arms, a carriage-tappet, jacks operable by said tappet for actuating said connections, rock-shafts and pin-bars, preparatory to a digit-indexing operation, groups of couplers normally lying depressed and passing under the rear ends of the pin-bars when operated, a system of yokes for lifting and depressing said couplers, each yoke including a transverse bar having guide-holes for the couplers, and also including arms forming a pivoted bail, each yoke being universal to its set of couplers and forming a part of a register-selecting train, means on the carriage to selectively operate the trains, to lift the groups of couplers into effective position, and to maintain the couplers elevated throughout the traverse of the computing zone by the carriage, and stops upon said couplers to arrest them at the driving movements, said stops formed to encounter the yokes which carry said couplers, said pin-bars having beveled portions below the points at which the pin-bars are engaged by the driving couplers.

19. In a combined typewriting and computing machine having a carriage and a series of registers, each register having a group of index pin-bars, a set of denominational rock-shafts extending across the machine, distributing arms upon said rock-shafts and arranged in groups, one set of arms for each set of pin-bars, each rock-shaft also having a single master-arm whereby it is operated, connections for operating said master-arms, a carriage-tappet, jacks operable by said tappet for actuating said connections, rock-shafts and pin-bars, preparatory to a digit-indexing operation, groups of couplers normally lying depressed and passing under the rear ends of the pin-bars when operated, and a system of yokes for lifting and depressing said couplers.

20. In a combined typewriting and computing machine, the combination with a series of registers and a traveling carriage, of a tappet on the carriage, a set of denomination-selecting jacks, a row of rods operable thereby, a set of transverse rock-shafts having master-arms operable by said rods, said rock-shafts having a downwardly and rearwardly inclined echelon formation, a row of distributing arms, there being one distributing arm on each rock-shaft for each register, a set of index pin-bars for each register, groups of normally idle individual couplers distinct from said pin-bars and forming a transverse row between the distributing arms and the pin-bars, the denominational order of the distributing arms being the reverse of the order of the master-arms, equal movements of the jacks producing equal advances of the index pin-bars, and means controlled by a device on the carriage for bringing the groups of couplers into use selectively while the pin-bars remain stationary.

21. In a combined typewriting and computing machine, the combination with a plurality of registers and groups of index pin-bars co-operative therewith, and a carriage, of non-traveling cam-plates individually mounted in a stationary group in the computing zone and each extending the length of said zone, there being only one cam-plate for each register, each cam-plate movable

independently of the others, adjustable units on the carriage having different groupings of teeth for moving the cam-plates selectively, adjustable universal carriage-tappets, denominational trains all operable by any of said carriage tappets, and means actuated by said cam-plates for bringing different groups of pin-bars under control of any one of said denominational tappets.

22. In a combined typewriting and computing machine having registers, sets of indexing devices therefor, a carriage, a set of ramifying denominational trains, having sets of couplers to enable said set of trains to control a plurality of sets of indexing devices, said couplers normally disconnected from said indexing devices, a set of cam-plates individually mounted in a stationary group in the computing zone and each extending the length of said zone, there being only one cam-plate for each register, each cam-plate movable independently of the others, adjustable units on the carriage having different groupings of teeth for moving the cam-plates selectively, operating trains extending from the cam-plates, bails operable by said cam-plate trains and effective to move said coupler sets to effective position relatively to the indexing devices, and a series of carriage-tappets each capable of operating all of said denomination trains.

23. In a combined typewriting and computing machine having registers, sets of indexing devices therefor, a carriage, denominational trains all operable in each computing zone by means on the carriage, and having sets of couplers to control any plurality of sets of indexing devices in any zone, a stationary group of cam-plates selectively operable by means on the carriage, operating trains extending from the cam-plates and including downwardly-thrusting rods forming a row and also including lever-arms placed side by side and operable by said rods, and nested rocking devices operable each independently of the others and connecting said arms to couple-operating means including shiftable bails disposed at properly spaced points across the machine, some of said rocking devices being in the form of bails, and others being in the form of rock-shafts upon which the bails are pivoted, said rock-shafts being rockable independently of the bails.

24. In a combined typewriting and computing machine having registers, sets of indexing devices therefor, a carriage, a series of tappets, a set of ramifying denominational trains operable by each of the tappets, one tappet at a time, and having sets of normally disconnected couplers for enabling said trains to control selectively any plurality of sets of indexing devices, a set of cam-plates individually mounted in a group in the computing zone and each extending the length of said zone, there being only one cam-plate for each register, each cam-plate movable independently of the others, and adjustable units on the carriage having different groupings of teeth for moving the cam-plates selectively, operating trains extending from the cam-plates, said operating trains including bails operable by said cam-plates, said couplers being controlled by said bails.

25. In a combined typewriting and computing machine having a series of registers and a letter-feeding carriage, a stationary group of register-selecting plates, trains operable, either singly or in any plurality, by said plates, denominational-selecting trains having a set of jacks located between the said register-selecting plates and the carriage, means adjustable on the carriage for depressing the register-selecting plates through-

- out the computing zone, and other means on the carriage for depressing the denomination-selecting jacks seriatim as the carriage feeds through the computing zone, said register-selecting plates being detachably mounted face to face directly upon the machine-frame in an accessible position in rear of the carriage and the set of denominational jacks.
26. In a combined typewriting and computing machine having a group of registers, sets of indexing devices therefor, a carriage, a series of universal tappets, a set of ramifying denomination trains all operable by each of the tappets, one tappet at a time, and having sets of couplers, each set of couplers being shiftable relatively to its indexing devices, to enable said set of trains to control selectively a plurality of sets of indexing devices, a stationary group of cam-plates all mounted face to face in the computing zone to be shiftable independently of one another and having means to control the condition of the individual sets of couplers, and a plurality of teeth upon the carriage for operating a plurality of cam-plates simultaneously, there being only one cam-plate for each register, and said teeth being distinct from said tappets, and capable of holding the cam-plates depressed throughout the computing zone.
27. In a combined typewriting and computing machine having a group of registers, sets of indexing devices therefor, a carriage, a series of universal tappets, a set of ramifying denominational trains all operable by each of the tappets, one tappet at a time, and having sets of couplers shiftable thereby while the indexing devices are stationary, to enable said set of trains to control selectively a plurality of sets of indexing devices, a stationary group of cam-plates mounted face to face and selectively operable singly or in groups by the carriage, a plurality of teeth upon the carriage for operating a plurality of cam-plates simultaneously, there being only one cam-plate for each register, and said teeth being distinct from said tappets, and capable of holding the cam-plates depressed throughout the computing zone, and a group of trains extending from the group of cam-plates, and including lever-arms connected to coupler-shifting means, said coupler-shifting means including controller bails disposed at properly spaced points across the machine for shifting the selected sets of couplers.
28. A unit formed for adjustment along the carriage of a combined typewriting and computing machine, said unit being in the form of an elongate structure substantially without lateral projections and having on one elongate side a tabulating tooth, and also having on said side a single permanent denomination-selecting tappet, and also provided with notches to removably receive register-selecting teeth, and having means to lock the teeth rigidly to said structure, to enable any tooth or teeth to be coordinated with said tappet.
29. In a combined typewriting and computing machine having a series of registers and a carriage, the combination of denomination-selecting jacks forming parts of trains each ramifying to the different registers, register-selecting cam-plates, and a tabulator-mechanism including a column-stop on the carriage, said column-stop forming part of an adjustable unit which also includes a single denomination-selecting tappet and a set of cam-plate-depressing teeth, said unit and teeth being arranged for varying the number and location of said teeth, the parts being arranged so that the carriage is arrested by the column-stop in position for operation of a denomination-jack by the tappet and for the depression of the selected cam-plate by a tooth, said single denomination-selecting tappet being distinct from said teeth, and each of said teeth being effective to hold depressed its associated cam-plate throughout the operation of all the jacks, the adjustable combination unit being supported upon front and rear racks placed one behind the other on the paper-carriage, the unit fitting in notches in both racks, the rear end of the unit having a ridge to insert in the notches in the rear rack.
30. In a combined typewriting and computing machine having registers, a carriage, tabulating mechanism, and indexing mechanism, the combination of a key on said machine at the rear of said carriage, said key extending in the direction of the travel of the carriage, and a tabulating unit upon said carriage having a denomination-selecting dog and also having a sliding fit upon said key to insure the proper engagement and accurate co-operation of the denomination-selecting unit with the jacks throughout the computing zone, said unit having a set of register-selecting teeth independent of said dog, register-selecting plates for selective depression by said teeth being mounted upon the machine-frame, each tooth, by co-operation of said key and unit, holding its plate accurately depressed throughout the zone.
31. In a combined typewriting and computing machine having a register and also having a letter-feeding carriage, a set of denomination-selecting jacks depressible by a carriage-tappet and an indexing mechanism, the combination with denomination-selecting trains operable by said jacks and including a set of guided rods engaged by said jacks, of a displaceable bar for guiding said rods at one end, means for moving said bar to swing said rods to permit the jacks to drop, the rods having at the ends guided by said bar adjustable heads to rest upon the tops of the rods, and means for automatically restoring said bar and thereby restoring the dropped rods and jacks to working positions.
32. A unit formed for adjustment along the carriage of a combined typewriting and computing machine, said unit being in the form of an elongate structure substantially without lateral projections and having on one elongate side a tabulating tooth, and also having on said side a denomination-selecting tappet, and also provided with notches to removably receive register-selecting teeth, said unit also having a key-forming to fit upon a stationary guide in the vicinity of the computing zone of the machine.
33. In a combined typewriting and computing machine having a series of registers and a carriage, the combination of denomination-selecting jacks forming parts of trains each ramifying to the different registers, a stationary group of register-selecting cam-plates, mounted facewise to each other, one plate for each register, register-selecting trains including rods engaged at their upper ends by the register-selecting cam-plates, said cam-plates being individually detachable and interchangeable, and a set of selective means adjustable along the carriage as a unit, for depressing one or more of said cam-plates and holding it depressed throughout the computing zone.
34. In a combined typewriting and computing machine, the combination with a plurality of reg-

isters and groups of index pin-bars co-operative therewith, and a carriage, of a single set of vertical denominational trains, a group of stationary plates, said carriage having means acting upon said plates for bringing different groups of pin-bars under control of said denominational trains, said cam-plates mounted in a pack in rear of the set of vertical denomination-selecting trains and in proximity thereto, said trains in rear of a set of tabulating stop-rods and in proximity thereto, and adjustable tabulator-stop units associated with said carriage and having tabulating stops at their forward ends and means between their ends for depressing the denomination-selecting trains, and also having adjustable means at their rear ends for depressing said cam-plates, means being provided for steadyng said tabulator-stop units for both the plate-selecting and the tabulating operations.

35. In a combined typewriting and computing machine having registers, sets of indexing devices therefor, a carriage, a single set of ramifying denomination jack trains having sets of connections to enable said single set of jacks to control any one or any plurality of sets of indexing devices, a single set of stationary cam-plates, means to enable said cam-plates to control the condition of the sets of connections selectively, and a series of devices individually adjustable along the carriage, for operating as a tabulator-stop, effecting denominational selection, and also operating one or more of said plates for simultaneously effecting single or multiple register-selection.

36. In a combined typewriting and computing machine having registers, sets of indexing devices therefor, a carriage, a single set of ramifying denomination jack trains, sets of connections to enable said single set of jacks to control a plurality of sets of indexing devices, a set of stationary cam-plates having means to control the condition of any one or more sets of connections, and a series of individually adjustable devices, one for each computing zone of the carriage, for operating as a tabulator-stop, effecting denominational selection, and also effecting register-selection, said adjustable devices each including a block having a series of notches, teeth differentially insertable by means of said notches in the block, and releasable means to fasten the inserted teeth, said teeth coacting with the cam-plates to bring into use any desired registers selectively in the zone for which the block is adjusted along the carriage.

37. In a combined typewriting and computing machine having a series of registers and a carriage, the combination of denomination-selecting jacks forming parts of trains each ramifying from a point adjacent the carriage to the different registers, a stationary group of register-selecting cam-plates, paired racks upon the carriage, and units each mounted adjustably upon said racks, to engage the teeth of both racks, each unit having cam-plate-operating teeth, and also having a column-stop device forked to fit upon one rack, one part of the fork formed to enter the notches in said one rack, and the other part catching over the top of the same rack, each unit having a beveled denominational-jack-selecting tappet between the column stop and the register-selecting teeth, said unit having locating and steadyng means to engage the notches in the other rack.

38. A unit formed for adjustment along the carriage-rack of a combined typewriting and

computing machine, and having a carriage-tabulating tooth, and also having a single denomination-selecting tappet, and also provided with notches to removably receive an array of individually settable register-selecting teeth, said single denomination-selecting tappet being distinct from the register-selecting teeth, and the latter being adapted to depress any one or more register-selecting cams and hold them depressed throughout a computation.

39. A unit formed for adjustment along the carriage-rack of a combined typewriting and computing machine, and having a carriage-tabulating tooth, and also having a single denomination-selecting tappet, and also provided with notches to removably receive an array of individually settable register-selecting teeth, said single denomination-selecting tappet being distinct from the register-selecting teeth, and the latter being adapted to depress any one or more register-selecting cams and hold them depressed throughout a computation, said tappet being between the tabulating tooth and the notches, and the end opposite said tabulating tooth being formed with guiding and supporting means.

40. A unit formed for individual adjustment along the tabulating-carriage rack of a combined typewriting and computing machine, and having a tabulating tooth for engagement with said rack, and also having a single denomination-selecting tappet, and also provided with a row of notches to receive a set of individually removable register-selecting teeth, a steadyng ridge being provided upon the top of said unit to fit in any of the notches of a companion supporting rack on the typewriter-carriage; said single denomination-selecting tappet being distinct from the register-selecting teeth, and the latter being adapted to depress any one or more register-selecting cams and hold them depressed throughout a computation.

41. A unit formed for adjustment along the carriage of a combined typewriting and computing machine, and having a tabulating tooth, and also provided with notches to receive teeth for depressing register-selecting cams, and also having a single denomination-selecting tappet, distinct from said teeth, for holding corresponding register-selecting cams depressed during the travel of the carriage through a computing zone, a steadyng ridge being provided upon the top of said unit to fit in the notches of a supporting rack on the typewriter-carriage, said unit also having a key-way to fit upon a stationary guide in the vicinity of the computing zone of the machine.

42. A unit formed for adjustment along the carriage of a combined typewriting and computing machine, and having a tabulating tooth, and also provided with notches to receive teeth for depressing register-selecting cams, and also having a single denomination-selecting tappet, distinct from said teeth, for holding corresponding register-selecting cams depressed during the travel of the carriage through a computing zone, said unit also having a key-way to fit upon a stationary guide in the vicinity of the computing zone of the machine.

43. In a combined typewriting and computing machine, the combination with a plurality of registers and groups of index pin-bars co-operative therewith, and a carriage, of a single stationary group of cam-plates, a single set of denominational trains operable by means on said carriage and including jacks, and means controlled by said

- cam-plates for bringing any plurality of groups of pin-bars under control of said denominational trains, said cam-plates parallel with one another and arranged on edge one behind another, and said carriage having cam-plate-controlling means including an adjustable block having notches, and cam-plate-selecting teeth adjustable to different notches to enable them to be effective upon a plurality of cam-plates simultaneously.
44. In a combined typewriting and computing machine, the combination with a plurality of registers and groups of index pin-bars co-operative therewith, and a carriage, of vertically slideable cam-plates, denominational trains including a row of thrust-rods and companion jacks in the form of slides, means controlled by said cam-plates for bringing different groups of pin-bars under control of said denominational trains, said cam-plates mounted adjacent the set of vertical denomination-selecting trains, said trains adjacent a set of tabulating stop-rods, said carriage being equipped with adjustable tabulator-stop units, said units having means for operating the denomination-selecting trains and also having means for selectively operating said cam-plates, said last two means being on the same side of said units and requiring substantial extension of the latter from a rack which locates the units, and means for supporting the outer ends of said units.
45. In a combined typewriting and computing machine having registers, sets of indexing devices therefor, a carriage, a set of ramifying denomination jack trains including settable connections to enable said set of jacks to control a plurality of sets of indexing devices, a set of cam-plates having means to control the condition of said settable connections, and adjustable means carried by said carriage, for operating as a tabulator-stop, effecting denominational selection, and also effecting register-selection, said means being in the form of a dog on said carriage universally adjustable in itself in respect to the number and identity of cam-plates to be operated thereby.
46. In a combined typewriting and computing machine having registers, sets of indexing devices therefor, a carriage, a set of ramifying denomination jack trains including settable connections to enable said set of jacks to control a plurality of sets of indexing devices, a set of cam-plates having means to control the condition of said settable connections, and adjustable means carried by the carriage, for operating as a tabulator-stop, effecting denominational selection, and also effecting register-selection, said adjustable means including a block carried by the carriage and having a series of notches, teeth differentially insertable in the block for actuating a certain cam plate or plates, to bring into use any desired registers in the zone for which the block is adjusted along the carriage, and means for removably fastening the teeth.
47. In a combined typewriting and computing machine having registers, sets of indexing devices therefor, a carriage, a set of ramifying denomination jack trains including settable connections to enable said set of jack trains to control a plurality of sets of indexing devices, a stationary set of cam plates grouped face to face in the computing zone and having means to control the condition of said settable connections, and teeth mounted on the carriage for selecting the registers, the teeth operating on said cam-plates and being removable from the carriage so as to leave any desired register out of use in any adding zone

of the work-sheet, said teeth operating simultaneously to couple the selected sets of indexing devices to the denominational trains, so that any number being typed may be run into all of the selected registers.

48. In a combined typewriting and computing machine having a register and also having a letter-feeding carriage, a set of denomination-selecting jacks compressible by means on the carriage, and an indexing mechanism, the combination with denomination-selecting trains operable by said jacks and including a set of guided rods engaged by said jacks, of a displaceable bar for guiding said rods at one end, means for moving said bar to swing said rods to permit the jacks to drop, said trains including separate links pressed down by the rods seriatim, during the travel of the carriage, the rods having adjustable heads to rest upon the tops of the links, the lower ends of said heads being beveled, and the upper ends of the lower links being also beveled, and means whereby said bar is automatically restored to cam up the upper rods by means of said bevels.

49. In a combined typewriting and computing machine having a set of registers, a carriage, indexing mechanism, and a general operator, the combination with denomination trains ramifying from the carriage to different indexing mechanism divisions for the various registers, register-selecting means for selectively rendering said divisions effective, said means including a set of register-controlling cam-plates compressible by means on the carriage, mechanism controlled by the general operator for causing the cam-plates to drop idly, said mechanism including a swing frame in which are guided links supporting said cam-plates, a cross-bar on said swing frame to swing up under arms 98 supporting said links, said cross-bar operating to lift said arms 98 and drop companion arms 99 together with elevated balls and denomination-selecting couplers controlled thereby, said balls remaining depressed throughout the remainder of the cycling of the general operator and until the carriage advances to a new computing zone, a disk being connected to be revolved by the general operator, said disk having a notch, a spring follower to run upon said disk and fall into said notch, and a spring to restore said follower to the notch to return the frame 251, 253 and associated parts to normal position, said follower being connected to said frame.

50. In a combined typewriting and computing machine having a set of registers, a carriage and indexing mechanism, the combination with a general operator for the computing mechanism, and denomination trains ramifying from the carriage to the various registers, of register-selecting means including a set of cam-plates, one for each register, means carried by the carriage for selecting said cam-plates, trains descending from said cam-plates, register-operating elements, said denomination trains including upper and lower rods, the upper rods resting on the lower rods, and means controlled by the general operator for swinging the lower rods rearwardly, the latter having beveled tops, and the upper rods having beveled bottoms, whereby the swinging of the lower rods drops the upper rods together with the cam-plates.

51. In a combined typewriting and computing machine having registers, sets of indexing devices therefor, a carriage, an adjustable carriage-tappet, a set of ramifying denomination trains

5 all operable by said carriage-tappet, and having sets of couplers to enable said tappet to control a plurality of sets of indexing devices, a stationary group of cam-plates mounted in the computing zone, one cam-plate for each set of couplers, each cam-plate extending throughout the computing zone, and having means to control the condition of its individual set of couplers, and a set of teeth distinct from said tappet and adjustable upon the paper-carriage for selectively operating said cam-plates, any single cam-plate or any plurality of said cam-plates being depressible by the carriage-teeth throughout the traverse of the computing zone for bringing a corresponding 10 register or registers into use.

52. In a combined typewriting and computing machine having registers, sets of indexing devices therefor, a carriage, a series of adjustable carriage-tappets, a set of ramifying denominational trains all operable by any one of said carriage tappets, said trains having sets of couplers to enable any one of said tappets to control a plurality of sets of indexing devices, each set of couplers being shiftable into and out of effective position relatively to its indexing devices, a stationary group of cam-plates mounted in the computing zone, one cam-plate for each set of couplers, each cam-plate extending throughout the computing zone and in facewise relation to the 20 other cam-plates, and having means to control the condition of its individual set of couplers, and units, each having a plurality of teeth for selectively operating a plurality of cam-plates simultaneously, said units being adjustable along 25 the carriage, said tappets being distinct from said teeth.

53. In a combined typewriting and computing machine having registers, sets of indexing devices therefor, a carriage, a series of tappets, a set of ramifying denominational trains all operable by each of the tappets and having sets of couplers shiftable to enable said trains to control simultaneously any plurality of sets of indexing devices, a stationary group of cam-plates 45 arranged face to face in the computing zone and selectively operable by means on the carriage, operating trains extending from the cam-plates and including coupler-shifting bails disposed at properly spaced points across the machine, lever-arms being included in said trains, and means connecting said arms to said bails.

54. In a combined typewriting and computing machine having registers, sets of indexing devices therefor, a carriage, a plurality of individually 50 adjustable carriage-tappets, ramifying denominational trains operable by the tappets, and having sets of couplers, a stationary group of cams, one or any plurality of which are selectively operable by carriage-teeth in a succession of 55 computing zones, trains extending from the cams, and bails shiftable by said cam-trains to maintain selected coupler-sets in effective condition, each cam being in the form of a plate having a dwell-portion engageable by the carriage-teeth, 60 to maintain any selected one or more coupler-selecting trains simultaneously in effective position as desired throughout any computing zone.

55. In a combined typewriting and computing machine having registers, sets of indexing devices 65 therefor, a carriage, a set of ramifying denominational jack trains operable by the carriage and having sets of couplers shiftable to enable said set of jacks to control any plurality of sets of indexing devices, a stationary group of cam-plates, means on the carriage to enable said

cam-plates to be selectively operated either singly or in multiple, and operating trains extending from the cam-plates, said operating trains including a series of nested coaxial rocking devices, some of which are rock-shafts, and other of which 5 are bails, said bails and rock-shafts being independently operable, and said rocking devices having means to shift the couplers.

56. A combined typewriting and computing machine having a computing base provided with 10 registers and a general operator, the typewriting machine detachably mounted upon the base and having a carriage, denomination jacks, and a set of carriage-controlled trains descending from a point adjacent the carriage into the computing 15 base, and including upper and lower combined sets of thrust rods, the upper rods being separable from the lower rods, a register-selecting set of trains also extending down from a point adjacent the carriage into the computing base, and 20 including upper and lower sets of rods, one set separable from the other, the separation of all of said rods permitting the typewriting machine to be lifted off from the computing base, each upper rod extending down at the back of the typewriting machine, and each lower rod extending up from the base, means on the carriage for operating the denomination jacks, means on the carriage for selectively operating the register-selecting trains, means for maintaining the joining ends of all the rods of the upper and lower sets in normal alignment, means for silencing the register-selecting trains, and means for detachably fastening the typewriter upon the base, the means for silencing the register-selecting trains 30 35 being mounted in the computing base, and the denomination-selecting jacks and corresponding upper thrust rods being mounted in the typewriting machine and lifted off from the base there- 40 with.

57. In a combined typewriting and computing machine having a set of registers, a carriage and indexing mechanism, the combination with denominational trains ramifying to different indexing mechanism divisions for the various registers, 45 means controlled by a device on the carriage for selectively rendering said divisions effective, and a general operator for the computing mechanism, of mechanism controlled by the general operator to disable said selecting means, the register-selecting means including a set of cam-plates 50 depressible by the device on the carriage, one for each register, said cam-plates forming part of register-selecting trains, each train including an upper member upholding the cam-plate and a lower member normally upholding the upper member, and said disabling mechanism including means controlled by the general operator for causing the cam-plates to drop idly, including a disk connected to the general operator and having a notch, said notch normally occupied by a follower, and means controlled by said follower for disconnecting said lower members of the register-selecting trains, and keeping them disconnected during the cycling of the general operator, causing upper members of said trains to drop together with the cam-plates. 60 65

58. In a machine of the class described, the combination with a plurality of registers, a carriage, and register-indexing means including a 70 dog on the carriage, denomination-selecting trains whereby said dog is operative to effect denomination-selection as the carriage traverses a computing zone, of a plurality of actuatable selectors, one for each register, selectively operable 75

- for rendering the indexing operation effective with respect to selected registers, and means on the carriage differentially settable relatively to said register-selectors to actuate any one or 5 more of the latter, said register-selectors being effective during the traverse of the computing zone by said dog.

59. In a machine of the class described, the combination with a plurality of registers, a carriage, and register-indexing means including a dog on the carriage, denomination-selecting trains whereby said dog is operative to effect 10 denomination-selection as the carriage traverses a computing zone, of a plurality of actuatable selectors, one for each register, selectively operable for rendering the indexing operation effective with respect to selected registers, and means on the carriage differentially settable relatively to 15 said register-selectors to actuate any one or

more of the latter, said register-selectors being effective during the traverse of the computing zone by said dog, said dog and settable means being combined in a unit adjustable along the carriage.

60. In a combined typewriting and computing machine having a set of registers, a carriage and indexing mechanism, the combination with distributive denomination trains ramifying from the carriage to different indexing mechanism 10 divisions for the various registers, register-selecting cam-plates carried by the carriage for selectively rendering said divisions effective, and a general operator for the computing mechanism, there being one register-selecting cam-plate for 15 each register, of means controlled by the general operator for causing the cam-plates to drop. 5

HENRY L. PITMAN.
